DESIGN FOR A REFRIGERATING CABINET

William W. Higham, Detroit, Mich., assignor to
Universal Cooler Corporation, Detroit, Mich.,
a corporation of Michigan

Application November 10, 1938, Serial No. 80,996

Term of patent 7 years

To all whom it may concern:

Be it known that I, William W. Higham, a citizen of the United States, residing at Detroit, in the county of Wayne and State of Michigan, have invented a new, original, and ornamental Design for a Refrigerating Cabinet, of which the following is a specification, reference being made to the accompanying drawings, forming part thereof.

Fig. 1 is a perspective view of a refrigerating cabinet showing my design.

Fig. 2 is a perspective view similar to Fig. 1 but showing the cabinet with the top in open position.

Fig. 3 is a top plan view of the cabinet.

I claim:

The ornamental design for a refrigerating cabinet, substantially as shown.

WILLIAM W. HIGHAM.
